**WIRING APPARATUS HAVING IMPROVED
WIRE-FEEDING MEANS**

Earl Raymond Kreinberg and William Thomas Nolan,
Harrisburg, and John Roy Vickery, York, Pa., assignors
to AMP Incorporated, Harrisburg, Pa.

Filed Apr. 27, 1964, Ser. No. 362,639
8 Claims. (Cl. 29—203)

This invention relates to the control of automatic wiring machines having improved wire feeding means which are used to form electrical connections between predetermined terminal posts on a panelboard containing a multiplicity of such terminal posts.

A variety of automatic and semi-automatic wiring machines are now known to the art of wiring panelboards and the like. In general, these machines comprise a device, herein designated as an applicator, for attaching a wire to a terminal post and means for moving the applicator relative to the panelboard in order to position the applicator in the vicinity of the terminal post to which a connection is to be made. The moving means may comprise a coordinately movable carriage on which either the applicator or the panelboard is mounted. In the operation of wiring machines of this general class, the applicator attaches the end of a wire to a first post (the A post) and is then moved relative to the panelboard until it arrives in the vicinity of the second post of a pair which are to be electrically connected (the B post). During such relative movement of the applicator, wire is drawn from a reel or other endless source and laid on or over the panelboard along a path corresponding to the path of relative movement of the applicator with respect to the panelboard. The applicator then attaches the wire to the B post to complete the electrical circuit from the A post to the B post.

The present invention relates to the control of the applicator of an automatic wiring machine during its relative movement from an A post to a B post and to the feeding of wire through the applicator during such movement. The principles of the invention are not limited to any particular type of applicator and are usable with applicators adapted to make wrap-type connections, welds and clip-type connections between the wire and the terminal post. The embodiment of the invention disclosed hereinbelow is particularly adapted to usage with an applicator of the type disclosed in the copending application of John R. Vickery, Serial No. 293,602, filed July 9, 1963, which forms a clip-type connection between the wire and the terminal post.

It is an object of the invention to provide an improved method and apparatus of controlling the applicator of an automatic or semi-automatic wiring machine. A further object is to provide an applicator control method and apparatus having an improved wire feeding arrangement and an improved wire feeding method. A further object is to provide a wiring machine for the wiring of panelboards which permits the laying of wire along diagonal paths, relative to the panelboard grid system, extending between terminal posts. A still further object is the achievement of precise control of the feeding and measuring of the wire drawn from a reel during relative movement of the applicator from one post to a second post. A further object is to provide a machine including means for attaching wire from a substantially endless source to a first terminal post, means for laying wire between the first terminal post and a second terminal post, means for severing the wire, and means for attaching the end of the severed wire to the second terminal post.

These and other objects of the invention are achieved in a preferred embodiment thereof comprising a coordinately movable carriage having an applicator mounted

thereon for making clip-type electrical connections between a wire and a terminal post. The carriage is moved in the X-direction (of an X-Y coordinate system) by means of an X-axis lead screw and is moved in the Y-direction by means of a Y-axis lead screw. Each lead screw is rotated in either direction by an electric motor controlled by an intelligence source, such as a punched tape, through the medium of a suitable numerical controller. Wire is fed through the applicator and towards the surface of the panelboard by means of an electric motor, the arrangement being such that the rate of feeding wire is always equal to the rate of movement of the applicator head relative to the panelboard whether the applicator is moving in a cardinal direction (the X-direction or the Y-direction) or is moving diagonally with respect to the board. The wire is guided towards the board through an outlet guide or nozzle in the applicator which is directed towards the surface of the board. The preferred embodiment of the invention includes means for shifting this nozzle in a cardinal direction a distance equal to one-half of the spacing between posts at the beginning of each cycle of travel of the applicator so that the nozzle can travel along a diagonal path and will lay the wire along a diagonal of the panelboard grid system without encountering any of the posts on the panelboard.

FIGURES 40 and 41 are views showing the manner in which wire is laid against the surface of the panelboard during a wiring operation, FIGURE 41 being taken along the lines 41—41 of FIGURE 40.

The accompanying drawings and the description below disclose an embodiment of the present invention which is integrated with an automatic wiring machine of the type disclosed and claimed in the copending Vickery application, Serial No. 293,602. Inasmuch as an understanding of this Vickery machine is necessary to an understanding

of the present invention, a description of the Vickery machine is presented below.

Referring first to FIGURES 30 and 31, an electrical connection between a terminal post 11 and a wire 13 is achieved by means of a clip 1 having a web 3 with upstanding sidewalls 5 on two opposite sides thereof. The sidewalls are reversely curled along their longitudinal edges 7 so that the clip is adapted to embrace the post and to hold the stripped end 15 of the wire against the surface of the post with the wire extending relatively downwardly along the post and emerging from the clip at its lower end as viewed in the drawing. Advantageously, an outwardly cupped insulation support 9 is provided on the web at its leading end for the accommodation of the end portion of the insulation of the wire.

The wiring machine, FIGURE 1, comprises an applicator or head 2 having a mounting bracket 4 secured thereto. The bracket 4 is suspended by means of a rod 6 from a bracket 8, which, in turn, extends from a coordinately movable carriage 10. As shown in FIGURE 33, the carriage 10 is slidably mounted on a first pair of rails 436 and is moved in either X-direction on these rails by means of a screw 437 which is threaded through a suitable boss on the underside of the carriage. Screw 437 is rotated by means of either one of two motors 438, 442, the motor 438 being of a relatively higher power than motor 442 and being coupled to a shaft 439 extending from the end of the power screw by means of a suitable belt 440. Motor 438 may be a conventional three phase induction motor adapted to rotate at only a single speed and rotates the screw 437 while the applicator is moving at its highest speed relative to the panelboard. Motor 442 is advantageously of the synchronous stepping motor type and is directly coupled to the shaft 439. Motor 442 rotates the screw 437 while its rotative velocity is decreasing, that is during the final portion of the travel of the applicator from an A post to a B post.

Rails 436, screw 437 and motors 438, 442 are mounted on a platform 445 which, in turn, is slidably mounted on a pair of rails 444 to permit movement of carriage 10 in the Y-direction. Platform 445 is moved along these rails in either direction by means of a screw 446 and motors 448, 452 which are similar to the motors 438, 442. Further details of the manner in which the motors 438, 442, 448, 452 are controlled and details of the cooperative relationship between these motors and the wire feed mechanism in the applicator 2 are presented below.

A panelboard 16, from which the terminal posts 11 project, is supported on a stationary table 14 which, in turn, is supported by a base 18. Wire 13 and terminal clips in strip form 1 are supplied to the applicator head 2 from reels which may be conveniently mounted on the carriage 10. In the disclosed embodiment, a pair of stabilizing plates 19 extend from the carriage and are secured to the applicator head to prevent lateral movement thereof and to assure precise positioning of the head with respect to the board 16.

The apparatus shown is capable of electrically connecting any two of the terminal posts 11 on the board 16. In general, the electrical connection between two posts is formed by first connecting the end of the wire 13 to the first post (herein designated as the A post), moving the applicator 2 to a position above the second or B post by means of the power screws, severing the wire 13, and connecting the end to the B post. The operation is carried out by means of a controller 20 which, under the influence of a source of intelligence in the form of a punched tape 21, directs the complete wiring operation of the panelboard 16. A conventional manual control console 22 is provided to permit manual operation of the apparatus when desired for experimentation or adjustment.

The principles of operation of applicator 2 can be grasped from a brief reference to FIGURES 26-29 and

are described at this juncture to provide a background for the detailed description of the applicator. Referring first to FIGURE 26 when the end of the wire 13 is to be connected to the first one of a pair of terminal posts (the A post), the wire is positioned as shown in FIGURE 26 in which its end portion is emergent from a shiftable nozzle or guide 102. This end portion of the wire is disposed in FIGURE 26 with its axis extending between a mandrel 400 and a clip transfer device 336. With the parts in these positions, the axis of the wire will extend transversely of the web of a clip 1 on the transfer device and transversely of the A post. Upon downward movement of a clip pusher 200, the clip is pushed from the transfer device past the wire, over the mandrel, and onto the terminal post. As the clip moves past the wire, the leading edge of the clip forces the wire against the upper side of the mandrel, the edges of which cut into the insulation. Subsequently, and as the clip moves over the mandrel, the clip pulls the end portion of the metallic core of the wire from the end section of insulation and through a sloping groove 404 in the mandrel. When the clip comes to rest upon the A post the stripped end of the wire will be clamped against the surface of the post.

While the applicator is being moved from the A post to the B post, the nozzle 102 occupies the position of FIGURE 27 in which its axis extends substantially vertically. Wire is fed through the nozzle during such movement of the applicator thereby to provide the necessary length of wire to extend between the two posts. After arrival of the applicator at the B post the nozzle is shifted from the position of FIGURE 27 to the position of FIGURE 28 in which it is on the opposite side of the mandrel from the side over which the clip is moved. It will also be noted in FIGURE 28 that the nozzle has been moved slightly beyond a shear blade 256 which is in alignment with the clip pusher 200 and which is movable with the clip pusher. Upon downward movement of the clip pusher 200 and the shear blade 256 to the position of FIGURE 29, the wire is severed by the shear blade while the clip moves downwardly onto the B post to make an electrical connection between the wire and the B post. After upward movement of the shear blade and the pusher from the position of FIGURE 29, the nozzle is moved back to the position of FIGURE 26 while the applicator is moved to the next post (the A post) of the next pair of posts which are to be connected. A detailed description of the mechanisms for carrying out the steps shown in FIGURES 26-29 will now be described.

Referring to FIGURES 2 and 3, the frame of the applicator head mechanism comprises three substantially parallel plates 24, 26 and 28. Plates 24 and 26 are secured in spaced-apart relationship to each other by suitable fasteners and spacers as shown. The H-shaped smaller frontal plate 28 is supported by means of brackets 23a, 23b, 23c and 23d extending from the plate 26, a vertical brace 25 being provided between the brackets 23b and 23c.

The cams which actuate the various mechanisms of the applicator are mounted on two parallel shafts 30 and 32. The shaft 30 extends through the plates 24, 26 and between the plates 26, 28 while the shaft 32 extends only to the plate 26. As shown in FIGURE 32, the shaft 30 has a sprocket 54 on its rearward end and the shaft 32 has a sprocket 56 on its rearward end. A chain 52 passes over the sprockets 54, 56 and over an idler sprocket 58 so that the two shafts rotate together during operation. Power is supplied to the applicator from the output shaft 48 of a motor having a sprocket on its end. This sprocket is coupled by means of a chain 49 to a sprocket 51 on the shaft 30. As indicated by the relative sizes of the sprockets 54, 56, the shaft 30 makes two complete revolutions for each single revolution of the shaft 32. The complete operating cycle of the apparatus during which an electrical connection is made to an A post and a B

post requires two revolutions of the shaft 30 and a single revolution of the shaft 32.

Referring now to FIGURE 4, a single revolution clutch on the shaft 30 comprises a pair of concentric sleeves 31, 33. A rotatable key 36 in the sleeve 33 is adapted to be rotated about its axis until it is received within a groove in the sleeve 31 thereby to engage the clutch. A spring 41 on the sleeve 31 biases a pin 39 which is integral with the key 36 in the manner such that the clutch is normally in engagement. A lever 38 pivoted at 40 to the plate 26 adjacent to the shaft 30 is normally biased by a spring 42 in a clockwise direction as viewed in FIGURE 4 towards the shaft so that its lower end engages the pin 39 and maintains the clutch in disengagement condition (as shown in the drawing) against the normal biasing force of the spring 41. When it is desired to engage the clutch for a single revolution of the shaft 30, a signal from the tape is supplied to a solenoid 46 driving the plunger 44 thereof leftwardly in FIGURE 4. This plunger is pivotally connected to the lever 38 and upon leftward movement of the plunger the lever is swung in a counterclockwise direction so that its lower end moves out of engagement with the pin 39. The spring 41 then causes the clutch to be engaged whereby the shaft 30 is driven through a single revolution and until the pin 39 again encounters the lower end of the lever 38. The signal supplied to the solenoid 46 is instantaneous so that immediately after engagement of the clutch and commencement of the single revolution of the shaft, the lever returns to its normal position and causes the clutch to be disengaged at the completion of the single revolution. As described below, the cams which actuate the mechanisms for forming an electrical connection with a terminal post (either the A or B post) are mounted on a shaft 30 so that this shaft must rotate two revolutions whenever a complete connection is made between two posts since each end of the wire is connected to one of the posts. The shaft 32 is rotated only one half of a revolution during each complete revolution of the shaft 30 since the cams on this shaft actuate the mechanisms which operate only once during a complete cycle.

The wire is fed from the reel 60 by means of a pair of feed rolls 62, 64 (FIGURE 2) through a guide tube 63 and through a flexible tube 67 which is disposed against the front surface of the plate 26. Roll 62 which is fixed with respect to the frame is contained in a housing 66 which, in turn, extends through an opening 68 in the plate 26. A flange 70 on the housing 66 (FIGURE 4) extends beyond the edges of the opening 68 on the rearward side of plate 26 and is secured to the plate by means of a fastener 72 and pins 74. Roll 62 is mounted on a shaft 76 for rotation therewith which shaft extends rearwardly of the plate 26 and has a gear 78 on its end in engagement with a gear 79 on the end of the output shaft of a motor 80. Adjacent to the gear 78, a gear 82 is provided on shaft 76 which meshes with a gear 84 on a shaft 65 on which the feed roll 64 is mounted. Advantageously, the gears 82, 84 have relatively large pitch teeth thereby to permit slight relative movement of the shaft 65 towards and away from the shaft 76 without complete disengagement of the gears.

Shafts 65 is rotatably supported in, and extends through, the upper end of a lever 86 pivoted at 90 to the rearward face of the plate 26. This lever extends downwardly past the shaft 30 and has a cam follower 92 mounted on an eccentric pin 94 at its lower end. Cam follower 92 engages a circular cam 96 mounted on the sleeve 31 for rotation therewith, the cam 96 having a notch on its periphery which is substantially diametrically opposite to the pin 39. Lever 86 is normally biased in a counterclockwise direction as viewed in FIGURE 4 by means of a spring 100 having one end secured to a pin in the plate 26 and having its other end secured to a pin in the lever 75 as shown in FIGURE 2. The spring 100 thus normally

biases the movable roll 64 against the surface of the roll 62 in which position wire is fed by the rolls through the guide tube 67, however, during periods of rotation of the shaft 30, that is when the clutch is engaged and the cam 96 is rotating, this cam will swing the lever in a clockwise direction about its pivotal axis 90 to disengage the wire feed.

As will become apparent as the description proceeds, wire will be fed by the rolls only while the applicator 2 is moving relative to the panelboard from an A post to a B post thereby to draw from the supply reel 60 a length of wire sufficient to reach between the two terminal posts being connected. When the applicator is positioned above a terminal post and a connection is being made, the shaft 30 will be rotating and the cam 96 will disengage the feed rolls from the wire.

The mechanism for shifting the wire nozzle 102 on the end of guide tube 67 to the several positions shown in FIGURES 26-29 will now be described with reference to FIGURES 5-10. The wire nozzle 102 is mounted in the end of a bar 104 which extends between the plates 24, 26 and slightly beyond the surface of the plate 26 as shown in FIGURE 27. This bar has rotatable cam rollers 106 thereon which are spaced apart by a distance equal to the spacing between the plates 24, 26. Bar 104 extends through aligned cam openings 108 in the two plates so that the followers are in engagement with the edges of these openings to guide the movement of the nozzle. Both of these openings 108 have generally arcuate upper sides 110 with three spaced-apart pockets 112, 114, 116 on their lower sides. Upwardly extending humps 118, 120 on the lower side of the cam openings separate the three pockets, the hump 118 being relatively higher than the hump 120.

A pair of spaced-apart ears 122 integral with the bar 104 extend from this bar and between the frame plates 24, 26. These ears 122 are received in aligned slots 124 in a pair of spaced-apart arms 126 which extend from a hub 128. The hub 128 is secured to a shaft 130 which extends through the hub and which has a bearing in the plate 26 and which extends through and has a bearing in a block 132 secured to the rearward side of the plate 24. An oversized opening is provided in the plate 24 through which a pair of fingers 138 project on each side of the shaft 130. These fingers have bevelled ends 140 which bear against the left-hand of the hub 128 as viewed in FIGURE 7. A complementary V-groove 142 extends across the hub 128 so that when the hub is rotated to a position such that the groove is in alignment with the bevelled ends 140 of the fingers, the hub is permitted to move leftwardly in FIGURE 7. When the hub is rotated from the position of FIGURE 7, the bevelled ends of the fingers 138 will move out of the groove 142 causing rightward movement of the hub. Hub 128 is normally biased leftwardly in FIGURE 7 by means of a spring 136 which surrounds the projecting rearward end of the shaft 130 and is effective between a head 134 on the end of the shaft and the opposed face of the block 132. Normally, and during most of the operating cycle, the bevelled ends of the fingers 138 are not seated in the V-groove 142, that is the hub and the arms are positioned relatively as shown in FIGURE 10. As is explained below, it is desirable to permit the hub to move leftwardly in FIGURE 7 until the ends of the fingers are seated in the V-groove during laying of the wire from the A post to the B post.

A link 144 extends between the arms 126 of the hub 128 and is pivotally connected by means of a pin 146 to the spaced-apart ears 122 of the bar 104. This link extends leftwardly in FIGURE 5 beyond its pivotal connection to the ears 122 and has a downwardly extending end portion 145 which defines a pocket 147 adjacent to pivotal axis 146. Link 144 is pivoted at its opposite end 150 by means of a clevis 148 to a two-part lever 152, 154, the two parts of this lever being pivotally connected at

156 in a manner which permits limited movement of the lower part 152 towards and away from the plate 24. The upper part 154 of the lever is pinned or otherwise secured to a shaft 158 which, in turn, is rotatably supported in the plate 24 and which extends through the plate 24 to the rearward face thereof. At its upper end, the part 154 of the lever is provided with a cam follower 160 which engages a cam 162 on the low speed shaft 32.

On the opposite side of the plate 24 from the side shown in FIGURES 5 and 6, an arm 164 is secured to and extends from the shaft 158. This arm has a follower 166 on its end which is engaged by a cam 168 mounted on shaft 32 on the rearward side of the plate 24.

FIGURE 5 shows the relative position of the nozzle 102 when the wire is connected to the A post. Towards the end of the process of forming this connection between the wire and the A post, the nozzle must be shifted from the position shown in FIGURE 5 to the position shown in FIGURE 6. Such shifting of the nozzle is effected by the cam 168 which has a rise 176 on its periphery for engagement with the cam follower 166 on the arm 164. As this rise 176 of the cam moves relatively past the follower 166, the shaft 158 is rotated counterclockwise so that the lower end of the lever 152, 154 swings along an arcuate path about the center of shaft 158. Such movement of the lever 152, 154 has the effect of pulling the bar 104 upwardly and over the hump 120 of the cam opening in the plates. The cam 168 is provided with a dwell portion which holds the bar 104 in the position of FIGURES 6 and 7, the position occupied by the parts during movement of the applicator from the A post to the B post. When the bar moves from the position of FIGURE 5 to the position of FIGURE 6, it also pulls the arms 126 along a clockwise path and thereby rotates the hub 128 and the shaft 130 relative to the block 132. As the hub moves into the position of FIGURE 6, the V-groove 142 is brought into alignment with the bevelled ends of the fingers 138 causing the hub, the bar and the nozzle to move leftwardly in FIGURE 7.

When the applicator arrives at the B post, the nozzle must be shifted to the position of FIGURE 9, which is effected by further rotation of the cam 168 causing further counterclockwise swinging of the lower end of the lever 152, 154. Because of the height of the hump 118 separating the center pocket 114 of the cam opening in the plates and the right-hand pocket 116, it is necessary to provide an auxiliary lifting mechanism for raising the bar 104 over the hump portion of the cam opening. This auxiliary lifting mechanism comprises a pair of lifting arms 178 which have end portions 182 extending beneath the bar 104 and on each side of the hub 128. These lifting arms 178 are substantially L-shaped and are pivoted at their upper ends on a pin 180 which extends between the plates 24, 26. Adjacent to the pivoted upper ends of these arms, a link 184 is pivotally connected at 183 to the arms and has its upper end pivotally connected at 186 to a lever 188. This lever is mounted for free rotation on the shaft 158 and has a cam follower 192 on its upper side which is engaged to the cam 194 on the shaft 32. The contour of the cam is such that during the brief interval when the nozzle is being shifted from the position of FIGURE 6 to the position of FIGURE 9, the lever 188 is permitted to move through a short arc in a clockwise direction. This motion of the lever is brought about by means of a spring 196 connected to the upper end of the link 184 and to a suitable pin on the plate 24. At the appropriate time in the cycle then, that is, when the nozzle is to be shifted from the position of FIGURE 6 to the position of FIGURE 9, the relieved portion of the cam 194 comes into contact with the roller 192 and the spring 196 is permitted to effect a slight upward pull on the lever 184. Such movement of the lever has the effect of swinging the arms 178 through a short arc in a counterclockwise direction so that the ends 182 of the lifting arms will lift the nozzle support structure over the hump 118.

After the wire has been attached to the B post and severed, it is, of course, necessary to shift the nozzle from the position of FIGURE 9 back to the position of FIGURE 5. Such shifting of the nozzle is effected by a cam 162 on the shaft 32 which engages the roller 160 on the upper end of the lever part 154; it will be apparent that the cam will cause the lever 152, 154 to be swung in a clockwise direction about its pivotal axis 158 and return the parts to the position of FIGURE 5. Since the cam 162 would ordinarily pass through the plane occupied by the lever 188, an arcuate cut-out section 198 is provided on the upper surface of this lever, the cam follower 192 being disposed behind the plane occupied by the cam 162.

Turning now to FIGURES 12 and 13, the clip pusher 200 has a generally channel-shaped cross-section and has a cavity or recess 202 at its lower end in which the clip is nested while it is being pushed. This clip pusher has an enlarged upper end 204 which is secured to an oscillatory shaft 206 having two rectangular center sections 207, 222 which are separated by a cylindrical shaft portion 223. The ends 210 of shaft 206 are of reduced diameter and are rotatably received within sleeves 212 (FIGURE 13). These sleeves are integral with a pair of blocks 214 which are slidably mounted on a pair of parallel guide rods 218 disposed between the plates 26 and 28. The left-hand one of these guide rods extends vertically between the bracket 23c and is received within a block 219 at its lower end which block is secured to a plate 26. The right-hand guide rod is supported at its upper end by the bracket 23d into which it extends and is supported at its lower end by a block 306 also secured to the plate 26. A torsion spring 220 surrounds the left-hand one of the sleeves 212 and has one end secured or anchored on the sleeve and its other end extending into a drilled hole in the shaft 206 to bias the shaft in a clockwise direction as viewed from the left in FIGURE 12. An L-shaped bracket 224 is fastened to the central rectangular section 222 of the shaft 206 and has a forwardly extending arm which is pivotally connected at 226 to a connecting rod generally indicated at 228. This connecting rod is pivoted at its upper end 230 to a rocker arm 232 on a stationary shaft 234. Connecting rod 228 is formed in two sections 236, 238 which are telescopically movable with respect to each other thereby to permit effective shortening of the length of the connecting rod. A compression spring 240 surrounds the connecting rod 228 and acts between shoulders provided on the two sections of the rod to bias the parts of the connecting rod to an extended position with respect to each other.

A cam roller 242 provided on the rocker arm 232 intermediate its ends is engaged by cams 244, 246 on the high speed shaft 30. The cam 244 has the effect of swinging the rocker arm 232 in a clockwise direction about the axis of shaft 234 to lower the shaft 206 and the clip pusher 200. The portions of this cam which effect lowering of the clip pusher extend between the datum points 248, 250 of the cam. The cam 246 raises the clip pusher upon engagement of the sections 252, 254 with the cam follower. It will be apparent from FIGURE 2 that the cam 246 is nested within the cam 244 which only partially surrounds the shaft 30.

It should be mentioned at this point that the clip pusher 200 is moved through a part of its downward stroke by the mechanism and linkage, described immediately below, which actuates the wire shear blade 256. It should also be mentioned that the connecting rod 228 is provided as two telescoping sections with an interposed spring for the purpose of preventing the imposition of an unduly high pushing force on the connector clip as it is moved over the terminal post. The significance of these features of the actuating mechanism for the clip pusher will become apparent from the description of the operating cycle of the apparatus.

FIGURE 14 shows the shearing mechanism for shearing the wire when an electrical connection is being made with a B post (FIGURES 28 and 29). The depending shear blade 256 is disposed beside and in alignment with the clip pusher 200 and has an upper shank portion 258 which is rearwardly offset at its upper end and is secured to a collar 260. This collar is pinned or otherwise mounted on a transversely extending shaft 262 which has its ends rotatably received in blocks 264. The blocks 264 are slidably mounted by means of bearings 266 on the guide rods 218 above the blocks 214 which support the shaft 206. As shown in FIGURES 15 and 16, the shaft 262 is disposed rearwardly of the shaft 206, that is, relatively towards the plate 26 as viewed in the drawing.

15 A block 268 is mounted on shaft 262 adjacent to collar 260, the shaft being rotatable with respect to the block. At its upper end this block has a pivotal connection 270 with a link 272 which extends upwardly and is pivotally connected at 274 to a rocker arm 276 on a stationary shaft 278. A cam follower 280 on the end of rocker arm 276 is engaged by the periphery of a cam 282 mounted for rotation on the shaft 30. This cam causes the rocker arm 276 to be swung in a counter-clockwise direction as viewed in FIGURE 14 about its pivotal axis 278 thereby to move the shaft 262 downwardly and to drive the shear blade 256 downwardly past the wire extending from the nozzle in FIGURE 28. The rocker arm 276 is normally biased in a clockwise direction by means of a spring as shown.

20 30 A block 288 is secured to, and extends forwardly from, the block 268. A screw 290 in this block extends downwardly from the underside thereof and has its axis extending transversely of the circular intermediate portion 223 of the shaft 206. During downward movement of the clip pusher 200 and the shear blade 256, the screw 290 comes into engagement with the portion 223 of the shaft 206 during the brief interval when the wire is being drawn over the mandrel. It is during this interval that the highest thrust is applied to the clip.

25 35 40 A pin 292 extends from the shank 258 and into the channel-shaped clip pusher 200. During upward movement of the shafts 206, 262 the blocks 264 reach the limit of their upward stroke prior to the blocks 214. Upon upward movement of the blocks 214 and the shaft 206 after the blocks 264 have come to rest, the circular portion 223 of the shaft 206 comes into engagement with the lower end of the screw 290. Since the shaft 206 cannot move upwardly after it has engaged the screw 290, it is caused to rotate through a relatively short arc in a counterclockwise direction as viewed in FIGURE 16 against the normal biasing force of the spring 220. Such rotation of the shaft 206 causes the clip pusher to swing through a relatively short arc away from the plane of the frame plate 26. The pin 292 which extends into the groove in the channel-shaped clip pusher causes the shear blade to swing in the same direction. This movement of the clip pusher and the shear blade is necessary in order to permit the wire nozzle and its associated supporting structure to be shifted from the intermediate position to the B position.

45 50 55 60 It is advantageous to provide a wire dressing means for pressing the wire downwardly against the surface of the board when it is connected to the B clip. The provision of this dressing means results in the positioning of the lead wire extending from the A post to the B post close to the surface of the board and below the level of the upper ends of the terminal posts. In the disclosed embodiment this dressing means is in the form of an open frame 281 having an upwardly extending shank 283 on one of its corners. This shank extends slidably through a block 285 mounted on a bar 287 which extends between and is secured to the blocks 214. A washer on the upper end of the shank 283 retains the shank in position while a spring 289 is interposed between a shoulder 291 and the underside of the block 285. As indicated in FIGURE 29,

the open frame 281 moves ahead of the clip pusher during downward travel of the pusher to dress the wires and position them against the surface of the board. The frame 281 will reach the limit of its downward travel prior to the time the clip pusher reaches the limit of its downward travel so that during the final portion of the downward stroke of the clip pusher, the block 285 moves relatively downwardly over the shank 283 with concomitant compression of the spring 289. It will be noted in FIGURE 16 that the shank 283 is in vertical alignment with the shaft 262 and the upper end of the shank is disposed adjacent to this shaft when the parts are in their normal positions. The relative movement between the shank and the block 285 is possible because of the fact that the shaft 262 reaches the limit of its downward movement prior to the time the shaft 206 reaches the limit of its downward movement as indicated on the timing diagram of FIGURES 33 and 34.

Referring now to FIGURES 17-19, the strip of terminal clips is fed from the reel mounted on the carriage 10 across the top of the upper stabilizing plate 19, over a guide roll, and thence through a channel-shaped groove 298 in a feed guide block 296. The block 296 is pivotally mounted adjacent to its upper end by means of a pin 300 on a vertical support bar 302 which is secured at its upper end to an inwardly projecting arm 304 on frame member 23d and is secured at its lower end to a fixed block 306 extending from the plate 26 (see FIGURE 3). A cover plate 308 on the guide block 296 extends over the guide channel 298 for a substantial portion of its length and adjacent to the lower end of the guide channel has an inwardly turned retaining finger 310 which lodges between adjacent clips in the strip and prevents retrograde movement of the strip. The clips are fed during each cycle past a notch at the lower end of the block 296 by means of a clip feed pawl 312 which is pivotally connected at 314 to links 316 on each side of the block 296. A torsion spring normally biases feed pawl 312 in a counterclockwise direction and into engagement with the strip of clips. The links are mounted on a common pivot pin 320 which extends through the block 296 and extend rightwardly in FIGURE 17 beyond the block and are pivotally connected at 322 to a connecting rod 324. The connecting rod extends upwardly beside the block 296 and is secured to an adapter piece 326 (FIGURE 2) at its upper end which projects forwardly from the axis of the rod 324. The adapter is, in turn, secured to a rod 328 which extends upwardly and is pivotally connected at 330 to a rocker arm 332 rotatably mounted on the shaft 334. A cam follower 333 on the end of rocker arm 332 engages the periphery of a cam 335 on the shaft 30. It will be apparent that for each complete rotation of the shaft 30, the rocker arm 332 is oscillated about its pivotal axis 334 thereby to reciprocate the feed pawl 312 and to feed the leading clip of the strip downwardly as viewed in FIGURES 17 and 19.

The leading clip is fed from the block 296 onto a T-shaped projection 336 of a transfer device described more fully below. After feeding of this leading clip onto the projection 336, the leading clip is separated from the strip by swinging the block 296 through a slight arc in a clockwise direction as viewed in FIGURE 17. Such swinging of the block 296 is effected by means of a bell crank 342 pivotally mounted at 344 on a pin which extends from a support block 346 which, in turn, is secured to the block 306. A screw 348 is threaded through the upwardly extending arm of the bell crank for engagement with the side of the feed guide block 296 while the rightwardly extending arm of the bell crank as viewed in FIGURE 17 is pivotally connected at 350 to a connecting rod 352. This connecting rod extends upwardly (FIGURE 2) and is pivotally connected at its upper end 354 to a rocker arm 356 disposed beside the rocker arm 332 on the shaft 334. A cam follower 358 on the end of the rocker arm 356 is engaged by the periphery of a cam 360

on shaft 30. A spring 362 connects the vertically extending arm of the bell crank and the lower end of the guide block 296 normally to bias the guide block in a counterclockwise direction about its pivotal axis 300 and against a stop bar 361 secured to, and extending from, the block 302. Upon relative upward movement of the connecting rod 352, the end of the screw 348 comes into engagement with the block 296 and swings this block through a short arc in a clockwise direction about its pivotal axis 300 whereby the axis of the strip of terminal clips disposed in the channel 298 is moved relatively leftwardly in FIGURE 17 with respect to the connector clip which has been fed onto the projection 336. As a result, this leading connector clip is sheared from the next adjacent clip and can be transferred to a position in alignment with the mandrel and the clip pusher.

Referring now to FIGURES 20-22, the T-shaped projection 336 which carries the clip from the loading station to a position in alignment with the pusher is integral with a bar 338 which, in turn, is secured to a plate 340. This plate is received within a deep slot or recess 366 in the block 306 which is secured to the frame plate 26. The plate 340 is pivotally mounted on a pin 364 which extends through the block 306 and through a recess 366, the plate itself being contoured and dimensioned such that the projection 336 will be shifted from the position of FIGURE 21 (where it is in alignment with the clip pusher) to the position of FIGURE 22 (the clip loading station) upon swinging of the plate about the axis of the pin 364. This swinging of the plate 340 is effected by means of a bell crank pivoted at 382 to ears 383 extending from the frame member 23c. A depending arm 380 of this bell crank is pivoted at its lower end 378 to a connecting rod 376 having a block 374 on its end. A pair of parallel plates 368 are secured to the block 374 and extend on each side of the block 306. A pin 370 extends through the ends of these arms, through arcuate slots 372 in the block 306 and through the plate 340. It will thus be apparent that upon counterclockwise movement of the bell crank about its pivotal axis 382, the projection 336 will be shifted from the position shown in FIGURE 21 to the position of FIGURE 22 while clockwise motion of the bell crank about its pivotal axis will result in the reverse movement of the clip carrying projection.

Such swinging of the bell crank is effected by a rocker arm 390 on a rocker arm shaft 392. This rocker arm is pivotally connected at 388 to one end of a link 386, the other end of this link being pivotally connected at 384 to the upper arm of the bell crank. A cam follower 396 on the end of rocker arm 390 is engaged by the periphery of the cam 398 on shaft 30. This cam causes the rocker arm 390 to swing in a counterclockwise direction only, the reverse motion of the rocker arm being brought about by a return spring 394 having one end hooked over a pin on the rocker arm and having its other end fixed to a pin in the plate.

The mandrel 400 (FIGURE 25) is of generally T-shaped cross-section and has a head portion 402 and a central rib 406 which is integral with mandrel arm 408. An inclined groove 404 extends partially along the surface of the head 402 from the upper end of the mandrel to facilitate cutting of the insulation of the wire and withdrawal of the conducting core thereof from the severed section of insulation while the clip moves over the mandrel.

The mandrel arm 408 is pivotally mounted at its right-hand end to permit limited arcuate motion of the mandrel towards and away from the terminal post with which an electrical connection is being made. An opening 412 extends through the mandrel arm adjacent to the mandrel itself to permit passage of the shear blade 256. Advantageously, a pair of upwardly extending ears 414 are provided on the mandrel arm on each side of the rib

406 to define a positioning and centering slot 416 for the wire when a connection is being made with a B post (FIGURES 28 and 29).

Rib 406 extends downwardly beyond the head 402 of the mandrel as indicated at 428 (see FIGURE 26). The side of this extension which is disposed against the terminal post to which a connection is being made has an obliquely extending surface 430, the length of the extension 428 and the length of the mandrel head 402 being such that when the mandrel is brought into position in alignment with the terminal post, a gap remains between the top of the post and the lower end of the mandrel head 402.

The limited arcuate movement of the mandrel bar and the mandrel is brought about by means of a cam 426 on shaft 30 which engages a cam follower on a rocker arm 424 on shaft 334. A connecting rod 418 is pivotally connected to this rocker arm at its upper end 417 and at its lower end 420 to the mandrel bar.

The reason for providing this limited arcuate movement of the mandrel stems from the fact that for best results, the axis of the terminal post should be in substantial alignment with the head 402 of the mandrel when the clip is pushed downwardly from the position of FIGURE 28 to the position of FIGURE 29. If the terminal posts are precisely positioned at their proper locations in accordance with the grid system of the panel, and if the applicator is precisely located above the terminal post with which a connection is to be made, the post and the mandrel will be properly located with respect to each other. As a practical matter, however, the posts will not always be positioned on the terminal board at the precise locations called for by the grid system of the terminal board since allowances must be made for manufacturing tolerances. Furthermore, the posts will not always extend precisely vertically from the board but may be bent slightly. It has been found, therefore, that it is desirable to slightly bend or flex the post under some circumstances in order to assure alignment of the post and mandrel under all possible conditions of misalignment. Specifically, the post is flexed slightly leftwardly in FIGURE 26 and if it is perfectly positioned and straight or if it is displaced rightwardly or bent rightwardly from its intended position. Such leftward flexure of the post will take place as the mandrel bar swings in a counterclockwise direction through a short arc whereby the bevelled surface 430 comes into engagement with the bevelled post. The effect of flexing the post under these circumstances (i.e., the post is properly positioned and straight or the post is rightwardly displaced from its intended position or bent rightwardly from the vertical) is to bring the upper end of the post into alignment with the head 402 of the mandrel. If the post is displaced slightly leftwardly from its proper position or if it is bent leftwardly as viewed in FIGURES 26 and 28, the post will not be flexed during arcuate movement of the anvil but will occupy a position in alignment with the head of the mandrel when the latter member comes to rest.

The above-described arcuate movement of the mandrel is also desirable since the mandrel must be raised above the level of the tops of the posts when the applicator 2 is moved relatively across the surface of the board from one post to another post. The arcuate movement of the mandrel into engagement with the post takes place immediately before the clip is pushed by the clip pusher across the mandrel and onto the post.

Referring to FIGURE 22, a pair of spring plates 399 are mounted by means of a block 403 on the frontal side of the frame plate 26 to the left, as viewed in the drawing, of the path of movement of the clip. These plates extend rightwardly on each side of the mandrel and are mounted on a level such that the mandrel is received between the divergently flared ends of the plates. The

upper edges of these plates are also divergently flared so that as the clip pusher moves downwardly past the mandrel, these fingers will be pushed slightly apart by the clip pusher. The function of these plates is to act as a guide means or retainer when the wire is being connected to the B post for maintaining the portion of the wire 13 which is adjacent to the mandrel with its axis in alignment with the center of the sloping groove 404 of the mandrel, see FIGURE 28. It should be added that these spring plates have been omitted from FIGURES 26-29 in the interest of clarity.

As best shown in FIGURE 2, the rocker arms 332, 356 and 424 are biased in a counterclockwise direction by springs as indicated. The action of the cams 335, 360 and 426 is to raise these rocker arms against the normal biasing force of the springs. The rocker arm 276 (FIGURE 14) is also biased in a clockwise direction by a spring as indicated and the cam 282 swings this rocker arm in a counterclockwise direction about its pivotal axis 278. The rocker arm 232 is not spring biased but is always under the positive control of the cams 244 and 246.

The operation of the applicator is as follows:

It is assumed that the parts are in the positions of FIGURES 5 and 26 at the beginning of the cycle with the applicator positioned above the A post and with the end of the wire extending as shown in FIGURE 26 between the mandrel and the clip supporting projection 336 of the transfer device. The parts will occupy these positions upon arrival of the applicator 2 at the A post after the completion of the preceding wiring operation. Upon arrival of the applicator at a position in alignment with the A post, the solenoid 46 is energized upon a signal from the tape 21 to permit engagement of the single revolution clutch on the shaft 30 to rotate this shaft through a single revolution and to rotate the shaft 32 through one-half of a revolution. Upon engagement of the clutch, the cam 96 moves relative to the cam follower 92 on the lever 86 thereby to deactivate the feed rolls 62, 64 while the end of the wire is being connected to the A post. During a very brief initial portion of the cycle the wire nozzle 102 will complete its shifting movement from the position of FIGURE 9 to the position of FIGURE 5 since this shifting motion was not entirely completed during the previous operating cycle. During this same initial portion of the cycle the clip pusher and the wire shear blade are swung by rotation of the shafts 206 and 262 until the pusher is in alignment with the mandrel and the shear blade is in alignment with the opening in the mandrel bar, this initial swinging of the pusher and the shear blade being effected by downward movement of the connecting rod 228. Thereafter, the shear blade is lowered by the cam 290 and the shaft 206 is pushed downwardly by the screw 290 which engages the circular portion 223 of the shaft 206. During this interval, while the clip pusher is being urged downwardly by the screw 290, the connecting rod 228 will be moved downwardly by the cam 244; however, little, if any, downward thrust is transmitted through the connecting rod during this interval for the reason that the spring 240 is relatively weak and easily compressed. The wire shear blade and the shaft 262 reach the limit of their downward travel after the shaft 30 has been rotated through an arc of about 140° by the time the clip will have been pushed from the transfer device, past the wire and partially over the mandrel. It should be mentioned that a relatively high downward push must be imparted to the clip while it is being pushed past the wire and over the mandrel since during this period, the clip compresses the insulation of the wire against the edges of the mandrel on each side of the tapered groove 404 and withdraws the metallic core of the wire from the severed section of insulation. The positive pushing effect of the screw 290 on the shaft 206 is required to develop this relatively high thrust.

After the shear blade reaches the limit of its downward stroke, it dwells during an interval of about 100° of rotation of the shaft 30 and the clip pusher 200 is pushed further downwardly under the influence of the cam 244. If the clip is being applied to a terminal post upon which one or more clips have previously been positioned and to which wires have previously been connected, the clip will come to rest against a previously applied clip prior to the limit of downward movement of the connecting rod 228. Further downward movement of the connecting rod without downward movement of the clip and the clip pusher is accommodated by relative telescoping movement of the two parts of the connecting rod into each other and compression of the spring 240.

The mandrel is arcuately moved against the top of the terminal post at about the same time as the wire shear blade reaches the lower end of its stroke. The nozzle begins to shift from the A position (FIGURE 26) towards the neutral position while the clip is being pushed over the mandrel by the clip pusher and the nozzle completes its shift to the neutral position at about the same time as the clip is moved from the mandrel onto the terminal post. This shifting of the nozzle from the A position to the neutral position during movement of the clip over the mandrel is desirable for the reason that during this brief interval, the clip will be pressing against the wire with a relatively high force, a high pushing force being required at this time because the insulation is being severed on the edges of the mandrel on each side of the sloping groove and the wire is being withdrawn from the severed section of insulation and compressed against the surface of the mandrel. It is desirable then to avoid the imposition of any tensile stresses on the portion of the wire extending from the nozzle 102 to the insulation support 9 of the clip during this withdrawing and ironing interval. The movement of the nozzle has the effect of avoiding such stressing of the wire extending from the lower end of the clip since the nozzle follows the clip while the nozzle is being shifted. After the nozzle reaches the neutral position, the clip must move relatively further down the post towards the surface of the panelboard and during this interval the clip may, in pulling on the wire, withdraw more wire from the reel and through the guide tube. Since the rolls are separated at this time, this additional wire can be freely withdrawn from the reel. Also, the slight tensile load imposed on the wire by the clip as it moves downwardly on the post and draws wire from the supply reel is not objectionable during this final portion of the downward movement of the clip since the compressing of the wire will have been completed after the clip moves from the 50 mandrel onto the terminal post.

The clip pusher is raised during an interval of rotation of the shaft 30 of about 45° and is simultaneously swung outwardly during the terminal portion of this interval. The clip pusher and clip shear blade dwell in their raised and swung-out positions during the remainder of the single revolution of the shaft 30.

At the beginning of the cycle the transfer mechanism is at the clip loading station (FIGURE 22) and is shifted to a position in alignment with the clip pusher during an interval in the early part of the cycle. The shifting of the transfer device, in fact, overlaps the initial portion of the downward stroke of the clip pusher and the shear blade. The transfer mechanism dwells in the position of FIGURE 21 until the shaft 30 has been rotated through an angle of about 270° and is then shifted back to the clip loading station. The next adjacent clip on the strip is then fed onto the projection 336 during the final 45° of rotation of the shaft 30.

At the conclusion of a complete revolution of the shaft 30 and after the operations described above have been carried out, the wire nozzle will be in the position shown in FIGURE 6 and feeding of wire through the flexible guide tube 67 will commence. The applicator is now moved in accordance with directions supplied by the tape

21 to the motors which rotate the positioning screws 12 for the carriage to a position above the B post. Upon arrival of the carriage at the B post, the single revolution clutch is again engaged upon a signal from the tape, the shaft 30 is rotated through a complete revolution, and the shaft 32 is rotated through one half of a revolution. The movements of the clip pusher, the wire shear blade, the clip transfer mechanism and the mandrel are the same during this second revolution of the shaft 30 as during the first revolution. The wire nozzle, however, is shifted during about the first 45° of this second revolution of shaft 30 to the position of FIGURE 9 and dwells in this position until the shaft 30 has been rotated through an angle of about 270° . Upon downward movement of the wire shear blade during this part of the cycle the wire extending from the nozzle, through the notch 416 and across the upper surface of the mandrel, is severed when the punch passes the edge 401. At the completion of the downward stroke of the clip pusher the cut end of the wire extending from the A post will then be connected to the B post. During the final 90° of rotation of the shaft 30 during this second portion of the cycle the nozzle is shifted towards the position of FIGURE 26 (the A position) but it does not arrive at this position until the commencement of the next operating cycle.

FIGURE 11 illustrates the significance of the arrangement shown in FIGURE 7 of mounting the rod 104 (on which the nozzle is mounted) on the shaft 130 in a manner such that the shaft 130 moves leftwardly when the nozzle is shifted to its neutral position (FIGURE 6). As explained above, upon rotation of the hub until the nozzle is in this neutral position, the V groove 142 of the hub is brought into alignment with the bevelled ends 140 of the fingers 138 and leftward movement of the shaft, and the nozzle 102 takes place under the influence of the spring 136. In FIGURE 11, the reference numeral 428 shows the position of the nozzle when an electrical connection is being made to an A post. It will be seen that the plane of the nozzle lies in a vertical plane 430 occupied by a row of terminal posts. When the nozzle is shifted to the neutral position it is swung until its axis extends vertically as shown at 432 and it is then moved laterally of its axis by virtue of the movement of the shaft 130 until it occupies the position shown at 434. When the nozzle is in this position, wire can be laid along any of the dotted line paths shown since no terminal posts lie on these paths. Oblique movement of the carriage and the nozzle must be at some predetermined angle which will avoid collision with the terminal posts. The precise angles or angle of oblique movement permitted will be dependent upon the dimensions of the posts and the grid spacings. Upon arrival of the nozzle at the B post, the shaft 130 and the hub 128 are rotated to position the nozzle in the orientation shown in FIGURE 9. Such rotation of the hub 128, causes the shaft to move axially against the biasing force of the spring 136 so that the nozzle will be positioned in the plane 430 and will be properly located for the operations of cutting the wire and connecting the cut end to the B post (FIGURES 28 and 29).

FIGURES 40 and 41 show the form assumed by the wire 13 during movement of the applicator relative to the board from an A post to a B post and illustrates the desirability of maintaining the rate of wire feeding at a level which is always equal to the relative speed of the applicator with respect to the panelboard. In these views, the nozzle is directed towards the surface of the panelboard 16 and it is assumed that the applicator is moving from left to right in an aisle bounded on one side by the terminal posts 11a, 11b and 11c, and 11a', 11b' and 11c' on the opposite side. Since the wire is being fed through the nozzle at a speed which is equal to the speed of the applicator, the portion of the wire 512 which is immediately adjacent to the nozzle will extend axially of the nozzle and substantially normally with respect to the surface of the panelboard. It is highly desirable that this

section 512 of the wire should project below the level of the upper end of the terminal posts in order that the trailing sections of wire 514 will be confined in the aisle defined by posts 11a, 11b and 11c on one side and by the posts 11d', 11b' and 11c' on the opposite side. If the applicator were to move upwards from the positions shown in FIGURE 41, the wire would extend around the base of the post 11b and would lie in the aisle defined by the post 11b' and would lie in the aisle defined by the posts 11b', 11b on one side and by the posts 11c', 11c on the opposite side. It is important to the achievement of a neat wiring job that the wire should be closely controlled while the applicator turns a corner and that the wire should follow the exact path of the applicator. In other words, the wire should not cut corners (as by being laid to the left of the post 11b) which the applicator has gone around. So long as the portion 512 of the emergent wire projects below the upper end of post 11b, the corner will not be cut and the wire portion 512 will project below the upper end of post 11b if the wire feed rate is maintained at a level equal to the applicator speed in accordance with the principles of the present invention. The maintenance of this synchronism of wire feed rate and applicator speed can be achieved by means of the speed control for the wire feed motor 80 which will now be described.

The control mechanism and circuitry for the wire feed motor 80 is integrated with the control mechanism for the X-screw and the Y-screw so that a brief explanation of the method of controlling these lead screws 437, 446 is desirable at this juncture. Accordingly, the arrangement for controlling the X-screw 437 is described briefly below, it being understood that a similar arrangement is used for control of the Y-screw.

Referring to FIGURES 33-36, a quantizer disc 454 of transparent material, such as acrylic resin, is mounted on the shaft 439 which extends from the screw. This disc is darkened over most of its area but has evenly spaced, unshaded or clear areas 456 on its periphery through which light can pass. A bracket 468 mounted on the platform 445 has a slot 469 therein into which the disc 454 extends. A pair of photoelectric cells 462 are mounted in the bracket 468 on one side of the slot 469 and in opposed relationship to light sources 470, the location of the cells 462 and the lights 470 being such that the shaded areas which separate the clear areas 456 on the disc 454 interrupt the light beams impinging on the cells. The cells 462 thus produce a series of pulses, the frequency or repetition rate of which will depend upon the spacing between the areas 456 and the speed of rotation of the X-screw 437.

The pulsating current from the cells 462 is fed into a comparator in the controller 20, this comparator comprising a command register and a position register. In a typical instance, data in the form of a definite number of pulses are fed into the command register to bring about a given travel of the applicator in the X-direction, these data being stored and retained in the command register until the desired travel has been accomplished. The motor 438 is then energized upon command from the controller to cause rotation of the X-screw 437 in the desired direction, the two photocells 462 being integrated into the circuitry in a manner such that the direction of rotation of the screw is sensed and controlled. During rotation of the power screw, the cells 462 count light pulses and produce the pulsating current referred to above which is fed into position register of the comparator. When the number of pulses counted approaches that number which were fed into the command register, the motor 438 is de-energized and the synchronous motor 442 is energized. This motor is integrated into the circuitry in a manner such that its speed decreases during the final portion of the X-travel so that the carriage is brought to a gradual, rather than an abrupt, halt. The motor 442 is de-energized when the number of pulses counted and fed into the

position register is equal to the number of pulses previously fed into the command register.

It should be noted that the control method briefly described above is known to the art and is commercially available in the Pratt & Whitney Model B numerically controlled drilling machine manufactured by Pratt & Whitney of New Haven, Connecticut. The Y-screw is actuated in substantially the same manner as the Y-screw and need not be described in further detail here.

The wire feed motor 80 is controlled by either of two sets of clear areas 458, 460 on the quantizer disc 454, the areas 458 being disposed radially outwardly from the areas 460 and between the peripheral areas 456 and the inner group of clear areas 460. As will be explained below, the group 458 of clear areas controls the wire feed motor 80 when the applicator is moving diagonally with respect to the grid system of the panelboard while the areas 460 control the wire feed motor when the applicator is moving in a cardinal (X or Y) direction of the grid system. It should also be explained at this point that the motor 80 is of the synchronous type and has a large number of poles so that it can be moved through an extremely small rotational increment. Motors of this type are commonly known as stepping motors and are well-known to the art, one suitable specific type being sold under the name "Slo-Syn," manufactured by Superior Electric Company of Bristol, Connecticut.

A photoelectric cell 464 is mounted in the bracket 468 at a location such that it is in alignment with the locus of the clear areas 458 and a second photoelectric cell 466 is similarly mounted in bracket 468 in alignment with the locus of the clear areas 460. Suitable light sources 463, 465 are provided in the bracket in the axial alignment with the cells 464, 466 so that either group of clear areas will permit passage of light to the cells.

The photoelectric cells 464, 466 form part of a circuit (FIGURE 37) containing the motor 80 and providing alternative current paths to the motor. Cell 466 is connected as shown in 472 with a shaping circuit 474, for example, of the Schmitt trigger type, the function of which is to change the pulsating current of varying amplitude which is produced by the cell 466 into a series of pulses of uniform amplitude. The output current of this shaping circuit is conveyed as shown at 476 to a speed selection circuit 478. This selection circuit is under the control of the tape as indicated at 479 and selectively permits either the signal from the line 476 or the signal from the line 492 (which is described below) to be transmitted to the motor. As will become apparent as this description proceeds, if the applicator is travelling in a cardinal direction (the X-direction or the Y-direction) the speed selector 478 will permit the signal in line 476 to pass through the line 482 to a binary coder 483. The signal then is transmitted to an amplifying means 486 and to the motor. If, on the other hand, the applicator is travelling diagonally, the signal from the line 492 will be permitted to travel to the motor 80 and the signal in the line 482 will be blocked. The essential function of the binary codes 486 is to convert the pulses in the line 482 into the correct switching sequence needed to drive the motor 80. The coder 483 and the amplifier 480 may be combined in a unit commercially available as a Slo-Syn Translator manufactured by Superior Electric Company of Bristol, Connecticut.

The number of clear areas 460 on the quantizer disc 454 which control the feeding of the wire when the applicator is moving in a cardinal direction is chosen such that the motor 80 will feed an amount of wire during each revolution of the quantizer disc which amount of wire is equal to the movement imparted to the applicator by one complete revolution of the X-screw 437. For example, if the applicator is moved 0.200" in the X-direction for each turn of the X-screw 437, and if six clear areas 460 are provided on disc 454, then each pulse should drive the motor 80 by an amount which will cause the feed

roll 62 to feed 0.033" of wire. This relationship can be achieved by judicious selection of the diameter of the roll 62, the size of the gear 79, and the number of poles in the motor 80.

When the applicator is moving at an angle of 45° with respect to the grid system of the panelboard, the control of the wire feed motor becomes somewhat more complex. During such diagonal movement of the applicator the pulsating signal from the photoelectric cell 464 is transmitted by a line 488 to a shaping circuit 474' which is similar in design and function to the previously described shaping circuit 474. The output signal from shaping circuit 474' is transmitted to a frequency dividing circuit in the form of a flip-flop 490, the function of which is to reduce the repetition rate of the signal in the output line 492 to a level at which it is one-half of the repetition rate of the signal produced by the photoelectric cell 464.

The necessity for the frequency dividing circuit 490 can best be understood if the required rate of wire feeding for diagonal applicator movement is considered as follows. If the applicator is to be moved at an angle of 45° relative to the grid system of the panelboard, the X-screw 437 and the Y-screw 446 will be simultaneously rotated upon command from the controller and at the same rate of rotation. FIGURE 38 illustrates by means of vectors the required movement of the carriage 10 (the X vector 492) and the movement of the platform 445 on the rails 444 (the Y vector 494) to produce diagonal movement of the applicator from the point 496 to the point 498. It is apparent then that when the applicator 2 is moving at an angle of 45° with respect to the grid system of the panelboard, the amount of wire which must be fed by the feed motor 80 is greater than either of the vectors 492, 494. Specifically, in the case of 45° movement of the applicator, the feed motor 80 must feed an amount of wire equal to $\tan 1/\cos 45^\circ X$ (distance 492).

In order to accomplish this relationship, the group of clear areas 458 on the quantizer disc must have $\sqrt{2} x$ (number of shaded areas 460). Since it is impossible to have a portion of a clear area on a disc, an even number of clear areas are provided in the group 458 and the frequency dividing circuit 490 is provided to make the necessary correction. To illustrate: assume, as above, that six clear areas 460 are provided in the inner ring of shaded areas to control the feed motor 80 during movement of the applicator in a cardinal direction and that every revolution of the screw 437 causes movement of the applicator for a distance of 0.200". For a given number of poles in the motor 80, the diameter of the wire feed roll 62 and the gearing should be such that six pulses supplied to the motor 80 will affect the feeding of 0.200" of wire as previously explained. If, however, the applicator is moving along an angle of 45° with respect to the grid system, the amount of wire required for 0.200" of travel in the X-direction and 0.200" of travel in the Y-direction (FIGURE 38) would be equal to $\sqrt{2} x 0.200$. The feeding of this amount of wire would require 8.5 pulses in the signal to the motor 80. As a practical matter 8.5 pulses cannot be produced directly by the photoelectric cell in a single revolution of the quantizer disc so seventeen pulses are produced by seventeen clear areas which interrupt the light beam impinging on the cell 464. These seventeen pulses produced in a given time interval are converted in the frequency divider 490 to a series of 8.5 pulses during each revolution of the screw which are fed through the speed selector and the binary codar to the motor 80.

It will be apparent that while the disclosed embodiment of the invention is adapted to feed wire at the proper rate for travel of the applicator in either one of the cardinal directions of the grid system or at an angle of 45° to these cardinal directions, the principles of the invention are equally applicable to diagonal movement at other angles with respect to the grid system.

For example, if it is assumed that it is desired to lay the wire against the panelboard at an angle of 30° in order to connect the points 500, 502 (FIGURE 39), the applicator would be caused to travel along the vector 510 by rotating the X-screw a distance corresponding to the vector 506 and simultaneously rotating the Y-screws a number of turns corresponding to the vector 508. During the interval of travel of the applicator from 500 to 502 it would be necessary to feed a length of wire by means of the motor 80 equal to this distance. Under such circumstances an additional group of clear area would be provided on the quantizer disc with the number of clear areas being sufficient to cause a number of pulses which would drive the motor 80 through the number of revolutions required to feed an amount of wire equal to the distance 510. The number of diagonal movement possibilities is theoretically unlimited but, from a practical standpoint, the number of possibilities is limited by the width of the posts and the spacing between the posts. For example, with the grid system and post size arbitrarily selected for purposes of illustration in FIGURE 11, diagonal movement at an angle of 45° and at an angle of 30° is practical. Diagonal movement at an angle less than 30° (say $\tan^{-1} 1/3$) might be impractical for the reason that the wire would not fit in the narrow aisle afforded for the wire path at this angle.

In the foregoing explanation, the quantizer disc 454 on the X-screw only is referred to, although an additional quantizer disc may be provided on the Y-screw as shown at 506. This quantizer disc on the Y-screw is provided only with a single group of clear areas which correspond to the clear areas 456 on the disc 454 and with a group of clear areas corresponding to the clear areas 460 of the disc 454. Thus, if the applicator 2 is moving in the Y-direction, the signal to the motor 80 will be supplied from the quantizer disc 506. If the applicator 2 is moving in either the X-direction or at an angle of 45° to the X-direction, the signal will be supplied from the disc 454. It will be apparent that the clear areas on the quantizer disc 454 which control the feeding of the wire when the applicator is moving diagonally need be provided only on one of the quantizer discs since both screws will be rotating whenever the applicator is moved diagonally.

From the foregoing description, it will be apparent that the present invention involves (1) the mechanical arrangement illustrated in FIGURE 11 for moving the outlet nozzle laterally in a cardinal direction after each wire connecting operation has been completed; and (2) the arrangement of controlling the speed of the wire feed motor 80 as described immediately above. The lateral movement of the nozzle 428 prior to traversing movement of the applicator places the nozzle in a position such that it is free to move in any of the cardinal directions of the grid system or in any one of several diagonal directions (at 45°, 30°, etc.).

Alternative methods of generating pulses in response to the movement of the applicator with respect to the panelboard could be used. For example, a roller could be mounted on the applicator and a fixed surface provided in a plane extending parallel to the plane of the panelboard 16. The roller would be provided with a pulse-generating means which would generate a series of pulses during its movement over the surface, the frequency of the pulses being directly responsive to the distance moved by the applicator. This series of pulses could then be utilized as in FIGURE 37 to drive a stepping motor as explained above. It should also be added that pulses generated in response to movement of the applicator could be employed in circuits alternative to the one shown in FIGURE 37 to drive a variable speed feeding means.

Changes in construction will occur to those skilled in the art and various apparently different modifications and embodiments may be made without departing from the

scope of the invention. The matter set forth in the foregoing description and accompanying drawings is offered by way of illustration only. The actual scope of the invention is intended to be defined in the following claims when viewed in their proper perspective against the prior art.

We claim:

1. Apparatus for making an electrical connection between two terminal posts on a panelboard comprising, a support for said panelboard, a substantially endless source of wire, an applicator having means for connecting said wire to a terminal post, applicator moving means for moving said applicator relative to said panelboard, pulse generating means for generating a series of pulses during relative movement of said applicator with respect to said panelboard, the repetition rate of said series of pulses being responsive to the speed of said applicator relative to said panelboard, wire feeding means for feeding said wire towards said panelboard, the rate of wire feeding by said wire feeding means being responsive to the repetition rate of said series of pulses, and means for supporting the foregoing means in cooperative relationship whereby, upon movement of said applicator relative to said panelboard from a first terminal post to a second terminal post, wire is laid on said panelboard along the path followed by said applicator.

2. Apparatus for making an electrical connection between two terminal posts on a panelboard comprising, a support for said panelboard, a substantially endless source of wire, an applicator having means for connecting said wire to a terminal post, X-axis and Y-axis moving means for moving said applicator relative to said panelboard, said X-axis and Y-axis moving means being independently operable to move said applicator in a cardinal direction relative to said panelboard and being simultaneously operable to move said applicator in a diagonal direction relative to said panelboard, pulse generating means for generating a series of pulses during relative movement of said applicator with respect to said panelboard, the repetition rate of said series of pulses being responsive to the speed of said applicator when said applicator is moving in a cardinal direction and when said applicator is moving in a diagonal direction relative to said panelboard, variable speed wire feeding means for feeding wire from said endless source towards said board, said wire feeding means being responsive to the repetition rate of said series of pulses, and means for supporting the foregoing means in cooperative relationship whereby, upon movement of said applicator relative to said panelboard from a first terminal post to a second terminal post at varying speeds, wire is laid on said panelboard along the path followed by said applicator.

3. Apparatus as set forth in claim 2 wherein said X-axis and Y-axis moving means comprises a pair of mutually perpendicular lead screws.

4. Apparatus as set forth in claim 2 wherein said X-axis and Y-axis moving means comprises a pair of mutually perpendicular lead screws, said pulse generating means comprising a light beam impinging on a photoelectric cell, and means for quantizing said light source in response to rotation of said lead screws, said wire feeding means comprising a stepping motor.

5. Apparatus for electrically connecting terminal posts which are mounted on a panelboard in accordance with a coordinate grid system comprising, an applicator having wire connecting means thereon for making an electrical connection between a wire and a terminal post, wire guide means in said applicator, said guide means being directed towards said panelboard and functioning to guide wire from a substantially endless source towards said panelboard, said guide means being normally in alignment with a row of said terminal posts and being disposed adjacent to a single post, means for moving said guide means laterally until said guide means is disposed between two adjacent rows of said posts after said wire

has been connected to a first terminal post, means for moving said applicator relative to said panelboard along a path extending between said posts from said first post to a position adjacent to a second post, pulse generating means for generating a series of pulses during movement of said applicator relative to said panelboard, the repetition rate of said series of pulses being responsive to the speed of said applicator when said applicator is moving in a cardinal direction and when said applicator is moving in a diagonal direction relative to said panelboard, variable speed wire feeding means for feeding wire through said guide means, said wire feeding means being responsive to the repetition rate of said series of pulses, means for moving said guide means laterally after said applicator has moved to the vicinity of a second post to which a connection is to be made until said guide means is disposed immediately adjacent to said second post, and means for supporting the foregoing means in cooperative relationship.

6. Apparatus for electrically connecting terminal posts mounted on a panelboard in accordance with a coordinate grid system comprising, wire guiding means having an outlet disposed adjacent to, and directed towards, said panelboard, said outlet being normally disposed adjacent to one of said posts, means for connecting wire emergent from said outlet to a first terminal post, means for moving said outlet and guide means in a cardinal direction of said grid system a distance equal to substantially one-half of the spacing between said posts in said cardinal direction, means for moving said outlet and said guide means along a straight line path extending between parallel rows of posts to a position in the vicinity of a second post and removed therefrom in a cardinal direction a distance substantially equal to one-half of the spacing between posts, means for shifting said outlet in said cardinal direction to position said outlet adjacent to said second post, means for projecting wire through said outlet during movement of said outlet at a rate equal to the rate of relative movement of said outlet with respect to said panelboard, and means for supporting the foregoing means in cooperative relationship whereby wire is laid against said panelboard along said path, and means for connecting said wire to said second post.

7. Apparatus for making an electrical connection between two terminal posts on a panelboard comprising, a support for said panelboard, a substantially endless source of wire, an applicator having means for connecting said wire to a terminal post, applicator moving means for moving said applicator relative to said panelboard, pulse generating means for generating a series of pulses during relative movement of said applicator with respect to said panelboard, the number of pulses generated being directly proportional to the amount of relative movement of said applicator with respect to said panelboard, wire feeding means for feeding said wire towards said panelboard, the amount of wire fed by said feeding means being directly proportional to the number of pulses generated, and means for supporting the foregoing means in cooperative relationship whereby, upon movement of said applicator relative to said panelboard from a first terminal post to a second terminal post, wire is laid on said panelboard along the path followed by said applicator.

8. Apparatus comprising wire feeding means for feeding wire towards, and laying wire on, a panel or the like comprising, a substantially endless source of wire, means for moving said wire feeding means relative to said panel, pulse generating means for generating a series of pulses during relative movement of said wire feeding means with respect to said panel, the repetition rate of said series of pulses being responsive to the speed of said wire feeding means relative to said panel, means for controlling said feeding means to feed wire therethrough at a rate responsive to the repetition rate of said series of pulses, and means for supporting the foregoing means in cooperative relationship whereby, upon relative movement of said

wire feeding means with respect to said panel from a first position to a second position, wire is laid on said panel along the path followed by said wire feeding means.
